CLAIM

The ornamental design for a fluorescent bulb disposal, as shown and described.

DESCRIPTION

FIG. 1 is a front elevational view of the fluorescent bulb disposal showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of container is for illustrative purposes only and forms no part of the claimed design. Portions of the cord have been omitted for ease of illustration in FIGS. 1, 2, 5 and 6.

FIG. 1

FIG. 2

FIG. 3

FIG. 4

FIG. 5

FIG. 6
